UNITED STATES PATENT OFFICE.

GEORGE E. BOURELLE, OF ELGIN, ILLINOIS.

WINDOW-CURTAIN BRACKET.

1,205,848.

Specification of Letters Patent Patented Nov. 21, 1916.

Application filed October 6, 1915. Serial No. 54,427.

To all whom it may concern:

Be it known that I, GEORGE E. BOURELLE, a citizen of the United States, residing at Elgin, in the county of Kane and State of Illinois, have invented new and useful Improvements in Window-Curtain Brackets, of which the following is a specification.

The invention relates to brackets, and more particularly to the class of window curtain brackets.

The primary object of the invention is the provision of a bracket of this character wherein the same can be readily and conveniently mounted in position upon a window frame without necessitating the use of screws and nails, thereby avoiding marring or otherwise defacing the said window frame when the bracket is in use.

Another object of the invention is the provision of a bracket of this character which is novel in construction so that it may be fastened to different sizes and styles of window frames and which will gracefully support the curtain in the hanging of draperies.

A further object of the invention is the provision of a bracket of this character wherein single or double draperies can be hung thereby and which may be permanently or detachably secured in place upon a window frame, the bracket being neat, ornamental and attractive in appearance.

A still further object is the provision of a bracket of this character which is extremely simple in construction, strong, durable, thoroughly reliable and efficient in its purpose and inexpensive in manufacture.

With these and other objects in view, the invention consists in the features of construction, and the combination and arrangement of parts hereinafter described, illustrated in the accompanying drawings and pointed out in the claims hereunto appended.

In the drawings Figure 1 is a fragmentary perspective view of a window frame showing a pair of the brackets constructed in accordance with the invention secured thereto and having attached thereon the resilient supporting elements for the hanging of draperies; Fig. 2 is a perspective view of one of the brackets detached from the

window frame; Fig. 3 is a perspective view of a modified form of bracket; Fig. 4 is a side elevation of a still further modification of bracket; Fig. 5 is a plan view thereof; Fig. 6 is an end view; Fig. 7 is a fragmentary perspective view of one of the brackets shown in Figs. 1 and 2 of the drawing, with the extensible sleeve mounted thereon; Fig. 8 is a vertical sectional view through the same; and Fig. 9 is a perspective view of still another modification of the invention.

Similar reference characters indicate corresponding parts throughout the several views of the drawings.

Referring to the drawings in detail, A 65 designates a portion of a window frame of the ordinary well known construction, upon which is fastened a pair of the brackets B hereinafter fully described. It is of course understood that two brackets are employed 70 for the supporting and hanging of a curtain or drapery, yet a description of a single bracket will suffice, as both are identical to each other in construction. Each bracket B comprises a single strip 10 of relatively stiff 75 material, preferably made from metal, bent on itself to form small and large curved stretches 11 and 12 respectively, with straight ends 13, the end of the stretch 12 being of considerably greater length than 80 the end of the stretch 11, and each end contains an aperture 14 for the engagement of the hook terminal 15 of a coiled expansion spring rod 16 upon which is adapted to be hung a curtain or drapery, the hook terminal 15 being readily detachable from the aperture 14 when it is desired to remove the rod 16 for any purpose. Secured to and spaced from the right 17 in the strip 10 on the stretch 12 is an L-shaped ear 18 formed 90 with right angular spurs 19 which are adapted to be driven into the outer edge of the vertical stile of the window frame A for the fastening of the bracket in position thereon without the use of screws or nails ordinarily 95 employed for this purpose.

The ear 18 is provided with a perforation 20 through which can be driven a nail or screw which may be used for permanently fastening the bracket in place upon the window frame.

now frame. It will be apparent that when the bracket is fastened upon the window frame as hereinbefore set forth it will not mar or deface the same, and either single or double draperies can be hung upon the rod 16 when connected thereto.

Slidably engageable with the straight end 15 of the stretch 12 of the bracket is a split sleeve 21 having a knob terminal 22, and in this manner the bracket is extensible for the hanging of overdraping. The sleeve 21 being adjustable permits the overdraping to be effectively hung either at narrow or wide windows.

18 In Fig. 3 there is shown a slight modification of the invention, wherein the bracket is formed from a single strip 23 bent on itself to provide a single rounded or curved stretch 24 having a reduced straight end 25 provided with a perforation 26 in which is detachably engaged the hook terminal 27 of the coiled spring rod 28, while the other end is bent to form an out-turned ear 29 having right angular spurs 30 which are 25 adapted to be driven into the window frame for the mounting of the bracket thereon, the ear 29 being provided with a perforation 31 to accommodate a nail or screw in the event that the bracket is to be permanently secured to the window frame, and this bracket is adapted to support a single curtain or drapery.

In Figs. 4, 5, and 6 there is shown a further modification of the invention 35 wherein the bracket is formed from a single piece 32 of relatively stiff material bent to provide an arm 33, foot 34 and ear 35, the latter being formed with right angular spurs 36 which are adapted to be driven 40 into the window for the fastening of the bracket thereon so that the foot 34 will overlie the outer face of the window frame to have its bearing thereon. The arm 33 is formed at its free end with a hook 36 for 45 detachably receiving the eye or hook terminal of the coiled extension spring rod hereinbefore described. The arm 33 is formed with spaced apertures 37 so that a plurality of extension rods can be connected thereto 50 for the hanging of double draperies or curtains should the occasion require. The ear 35 is provided with an aperture 38 through which can be driven a nail or screw for the permanent fastening of the bracket on the 55 window frame. It is of course understood that in lieu of the extensible rod hereinbefore described the ordinary rod or solid rods can be employed and the same can be engaged in the perforations 37 in the arm 60 33 of the bracket. Also it will be apparent that either a single or double rod can be attached to the brackets and when the curtains or draperies are hung thereon it will not interfere with the working of the window shade as 65 the same can be pulled down without show-

ing the curtain from the outside of the window frame. The bracket can be readily and easily attached to the edge of the window frame or in any other desired position by the spurs which are driven into the edge 70 of the said window frame or other desired place, while the foot of the bracket rests against the outer face of the window frame and when force or pressure is applied to the bracket the tighter the same will grip the 75 window frame so that there is no chance of the loosening of the bracket from place thereon, nor will the said window frame become marred or defaced.

In Fig. 9 there is shown a still further 80 modification wherein the bracket, which is formed from a single piece of material, preferably metal, in strip form, 38, is bent to form the inner and outer goosenecks 39 and 40, respectively, both having straight 85 extensions 41, the extension on the outer gooseneck being of greater length than the extension on the inner gooseneck, and fixed to the inner end of the outer gooseneck is a shade roller holder 42, the outer end of 90 which is formed with an ear 43 having spurs 44 which are adapted to be driven into a window frame for the mounting of the holder and bracket thereon without the use of nails or screws. 95

From the foregoing description, taken in connection with the accompanying drawings, it is thought that the construction and manner of use of the device will be readily apparent and further description has therefore been omitted. 100

Having thus described my invention, I claim:

1. A bracket of the class described comprising a relatively stiff strip bent on itself to form inner and outer loop-like stretches disposed in the same plane with each other, the inner stretch being spaced for a greater portion of its length from the outer stretch, both of said stretches having reduced end portions and provided with perforations, one reduced end portion being of greater length than the other, an L-shaped ear carried by the other loop portion and having spurs for biting engagement in a window frame and also having an aperture for receiving a fastener, and a spring adapted for detachable engagement with either of the perforations in the reduced portions. 115

2. A bracket of the class described comprising a relatively stiff strip bent on itself to form inner and outer loop-like stretches disposed in the same plane with each other, the inner stretch being spaced for a greater portion of its length from the outer stretch, both of said stretches having reduced end portions and provided with perforations, one reduced end portion being of greater length than the other, an L-shaped ear carried by the other loop portion and having 125

spurs for biting engagement in a window frame and also having an aperture for receiving a fastener, a spring adapted for detachable engagement with either of the perforations in the reduced portions, and a split sleeve slidable upon one reduced portion and having a knob terminal.

In testimony whereof I affix my signature in presence of two witnesses.

GEORGE E. BOURELLE.
